UNITED STATES PATENT OFFICE

160,439

SACHET

Olivia Grant Smith, Morristown, N. J.

Application March 18, 1950, Serial No. 8,608

Term of patent 7 years

(Cl. D86—10)

To all whom it may concern:

Be it known that I, Olivia Grant Smith, a citizen of the United States of America and resident of Morristown, county of Morris, State of New Jersey, have invented a new, original, and ornamental Design for a Sachet, of which the following is a specification, reference being had to the accompanying drawings, forming part thereof.

I claim:

The ornamental design for a sachet as shown.

OLIVIA GRANT SMITH.
